EXPANDABLE BINDER FILING DEVICE

Stephen C. Stephanson, New York, N. Y.

Application September 2, 1950, Serial No. 182,961

2 Claims. (Cl. 129—41)

1

This invention relates to new and useful improvements in expandable filing devices.

More particularly, the present invention proposes the construction of an expandable filing device having spaced supports between which spaced parallel straps are extended in a manner to have the material to be filed removably mounted on the straps between the supports.

Another object of the present invention proposes constructing the filing device as a book, 10 employing the basic principle of the present invention set forth in the paragraph preceding.

A still further object of the present invention proposes arranging the spaced parallel straps so that their length between the spaced supports 15 can be varied—either increased or decreased—permitting greater amounts of material to be filed or some of the material to be removed, as desired.

Still another object of the present invention proposes mounting each item of material to be filed on a post hanger with means for removably mounting the post hangers in position on the spaced parallel straps in a manner so that any one filed item can be conveniently removed or a new item filed in its proper position without disturbing any of the other filed items.

A further object of the present invention proposes clips for engagement with different items to be filed—such as: relatively thin booklets, 30 thick books, stacks of related sheets, a single sheet of paper or the like—and which in turn are removably connected with the post hangers in a manner so that the filed items can be separated from the post hangers for use independently of the filing device and related post hanger when desired.

The present invention further proposes the provision of partition sheets for independent removable mounting on the spaced parallel straps 40 between groups of filed material falling into different classifications in a manner to separate the various groups.

When the filing device is constructed in the form of a book, it is proposed to construct the 45 spaced supports in the form of hollow book covers with a flexible back sheet extended parallel with the spaced parallel straps and into the hollow book covers the back edge thereof in a manner so that the back sheet acts as a back for the assembled filing book.

Still further, the present invention proposes the provision of a means within one of the hollow book covers for clamping the excess lengths of the spaced parallel straps and the flexible back 55

2

sheet in position within that one hollow book cover and adjustable means within the other of the hollow book covers engaged with the ends of the spaced parallel straps and the flexible back sheet in a manner so that the effective length of the parallel straps and the flexible back sheet can be adjusted as desired within fractions of an inch.

Another object of the present invention proposes extending a binding belt parallel with the flexible back sheet and the parallel straps and which acts on the aforementioned adjustable means when pulled to release the same so that further pulling on said belt will draw the hollow book covers into the desired adjusted positions with relation to the flexible back sheet and the parallel straps.

It is a further object of the present invention to construct a filing device of the type described which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the filing device in the form of a book constructed in accordance with the present invention.

Fig. 2 is a plan view of the book in open condition with parts of the inserts broken away to reveal interior constructions.

Fig. 3 is an inside elevational view of the front cover of the book with its inner cover portion in the open position.

Fig. 4 is a view similar to a portion of Fig. 3, but with the reserve lengths of the back sheet and straps illustrated in their completely extended position.

Fig. 5 is an enlarged partial horizontal sectional view taken on the line 5—5 of Fig. 2.

Fig. 6 is a perspective view of one of the clamp pieces used in connection with the front cover.

Fig. 7 is an inside elevational view of the back cover of the book with its inner portion in the open position.

Fig. 8 is an enlarged partial vertical section view taken on the line 8—8 of Fig. 7.

Fig. 9 is an enlarged partial horizontal sectional view taken on the line 9—9 of Fig. 7.

3

Fig. 10 is an enlarged partial vertical sectional view taken on the line 10—10 of Fig. 7.

Fig. 11 is a perspective view of one of the L-shaped toothed bars used in the back cover.

Fig. 12 is an enlarged partial horizontal sectional view taken on the line 12—12 of Fig. 1.

Fig. 13 is an enlarged partial horizontal sectional view taken on the line 13—13 of Fig. 1.

The filing device, in accordance with the form of the invention illustrated in Figs. 1 to 13, inclusive, is in the form of a loose-leaf book 50 having end supports in the form of a hollow front cover 51 and a hollow back cover 52. Extended between the back edges of the covers 51 and 52 there is a horizontal pair of vertically spaced straps 53, of flexible material, upon which the items to be filed are to be supported. The straps 53 are preferably formed of any durable cloth webbing or a synthetic resin. Coextensive with the straps 53 there is a back sheet 54 which extends along the outer face of and covers the straps 53, as shown in Fig. 1. The back sheet 54 is made of rubberized cloth, leather, synthetic leather or a synthetic resin in sheet form.

In addition to the back sheet 54 and the straps 53, there is a binding belt 55. The belt 55 is preferably formed of leather and is extended along the inner face of the back sheet 54 substantially midway between the straps 53. The utility of the belt 55 will become clear as this specification proceeds.

The front cover 51, as shown most clearly in Figs. 2 to 5, 12 and 13, is made of a top channel member 56, a bottom channel member 57 and vertical channel members 58 and 59 extended between the ends of the channel members 56 and 57. Adjacent ends of the channel members 56, 57, 58 and 59 are welded together and from Figs. 12 and 13 it will be noted that the channel member 59 is thinner than the other channel members. The channel member 59 is secured to the ends of the channel members 56 and 57 so that its inner face is flush with the inner face of the channel members 56 and 57. Secured to the outer faces of the channel members 56 and 57 there is an L-shaped strip of metal 60 having one of its arms 61 extended into the hollow of the front cover 51. The relationship of the L-shaped strip 60 to the narrower channel 59 is such that an opening 62 exists between the adjacent faces of those parts. From Fig. 13, it will be noted that the straps 53 and the back sheet 54 enter the hollow of the front cover 51 through the opening 62. The intermediate wall of the channel member 59 is formed with a hole 63, see Fig. 12 particularly, through which the binding belt 55 enters the hollow of the front cover 51. After entering the hollow of the front cover 51, the back sheet 54, the straps 53 and the binding belt 55 pass across the free edge of the inwardly directed arm 61 of the L-shaped strip 60 and comprise the excess of those parts for permitting the capacity of the book to be expanded.

The outer face of the front cover 51 between the L-shaped strip of metal 60 and the outer edge of the channel member 58 is closed by a plate 64 which is secured to the adjacent flanges of the channel members 56, 57 and 58 by means of rivets 65, see Fig. 5. The plate 64 is formed of metal or a suitably colored piece of synthetic resin.

Within the hollow of the front cover 51, the straps 53, the back sheet 54 and the binding belt 55 pass beneath a stationary rod 66, see Figs. 3 to 5. The rod 66 is fixedly mounted between the intermediate arms of the channel member 56 and

4

57 and is extended parallel to the channel members 58 and 59 but closely adjacent the channel member 58. The ends of the straps 53, the back sheet 54 and the binding belt 55 after passing beneath the rod 66 are secured together between superimposed metallic strips 67 and 68. Passing through the metallic strips 67 and 68 and the back sheet 54 and particularly at the locations of the straps 53 and the belt 55 there are rivets 69 joining those parts together. The innermost flanges of the channel members 56 and 57 are formed with cutouts 70, see Figs. 3 and 5, at the ends of the rod 66. The cutouts 70 permit the ends of the metallic strips 67 and 68 and the top and bottom edges of the back sheet 54, after the straps 53, the back sheet 54 and the belt 55 have been doubled back over the rod 66, to be slipped back into the channel members 56 and 57, as shown in Fig. 3, providing a storage for the excess lengths of the straps 53, the back sheet 54 and the belt 55.

The inside face of the front cover 51 is closed by a cover plate 71 which is preferably formed of the same material used for forming the plate 64. The vertical edge of the cover plate 71 at the back of the book is formed with spaced hinge lugs 72 which are fitted into complementary hinge lugs 73 formed in a hinge strip 74. The hinge lugs 72 and 73 are pivotally connected together by means of a hinge pin 75 extended through aligned holes formed in the lugs 72 and 73. The hinge strip 74 is extended along the back or outer faces of the channel member 59, see Figs. 12 and 13, and is formed along its edge, remote from the edge formed with the hinge lugs 73, with spaced hinge lugs 76 engaged between complementary spaced hinge lugs 77 formed on the channel member 59, see Figs. 3 and 12. The hinge lugs 76 and 77 are pivotally connected together by means of an elongated hinge pin 78 passed through aligned holes formed in the hinge lugs 76 and 77. The relationship between the hinge lugs 76 and 77 is such that with the cover plate 71 in its closed position there is a clearance between the adjacent faces of the channel member 59 and the hinge strip 74, see Figs. 12 and 13 for the passage of the straps 53. Intermediate of its ends, the hinge strip 74 is formed with a cutout 79, see Figs. 3 and 12, for the passage of the binding belt 55 so that it can enter the hole 63 in the channel member 59.

In alignment with the inwardly directed arm 61 of the L-shaped strip of metal 60, cover plate 71 is formed with an inwardly directed flange 80, see Figs. 3 and 12. At points aligned with the straps 53 and the belt 55, the flange 80 has secured thereto by means of rivets, short pieces of hard metal 81. The pieces of metal 81 have edges projecting beyond the free edge of the flange 80 and those projecting edges are formed with spaced teeth 82 which, in the closed position of the cover plate 71, are pressed into the surfaces of the straps 53 and the belt 55 securing those parts in position with relation to the free edge of the inwardly directed arm 61 of the L-shaped strip of metal 60. Thus, when the cover plate 71 is in its closed position, the excess lengths of the straps 53, the back sheet 54 and the binding belt 55 are locked in position within the hollow of the front cover 51.

Means is provided for releasably retaining the cover plate 71 in its closed position so that the same can be opened when desired disengaging the teeth 82 from the straps 53 and the belt 55 so that the excess lengths of the straps 53, the

5

back sheet 54 and the belt 55 can be withdrawn from the hollow of the front cover 51 when needed. That retaining means is comprised of elongated horizontally disposed slots 83, see Figs. 2, 3 and 5, formed in the top and bottom edges of the cover plate 71 adjacent the free edge thereof. L-shaped keys 84 have neck portions 85 turnably mounted on the adjacent flanges of the channel members 56 and 57 and elongated head portions 86 at the free outer ends of the neck portions 85. The head portions 86 correspond in shape to the shape of the slots 83 in the cover plate 71. In one turned position of the neck portion 85, the head portions 86 are aligned with the slots 83 so that the cover plate 71 is free to be pivoted between open and closed positions. However, when the neck portions 85 are turned into positions in which the head portions 86 are disaligned from the slots 83, as shown in Fig. 5, the cover plate 71 will be retained in a position in which it closes the open inner side of the front cover 51.

From the front cover 51, the straps 53, the back sheet 54 and the binding belt 55 pass across the back edges of any items inserted between the front cover 51 and the back cover 52 and then into the hollow of that back cover 52. Basically, the back cover 52 is of substantially the same construction as the front cover 51 and is comprised of a top channel member 87, a bottom channel member 88 and vertical channel members 89 and 90 extended between the ends of the channel member 87 and 88, see Figs. 7 to 13. The adjacent ends of the channel members are welded together, and as in the case of the front cover 51, the channel member 90 is thinner than the other channel members and secured to the adjacent ends of the channel members 87 and 88 with its inner flange flush with the inner flanges of the channel members 87 and 88. The outer side of the back cover 52 is closed by a plate 91 secured to the outer flanges of the channel members 87, 88 and 89 by means of rivets 92, see Figs. 8 to 10. The plate 91 is preferably made of the same material used for forming the plate 64 and the cover plate 71 of the front cover. The relationship between the plate 91 and the adjacent flange of the channel member 90 is such that an opening 92, see Figs. 12 and 13, is formed through which the back sheet 54 enters the hollow of the back cover 52.

Set into the back cover 52 there is an inner frame having channel members 93, 94, 95 and 96 extended parallel to the channel members 87, 88, 89 and 90 of that back cover. All of the channel members 93, 94, 95 and 96 are of a thickness corresponding to the thickness of the channel member 90 and have their adjacent ends welded together. Adjacent the channel member 98, the corners of the inner frame is formed with lugs 97, see Fig. 7, of a width corresponding to the spacing between the flanges of the channel member 90 which are received within the channel member 98. At its opposite corners, the inner frame is formed with outwardly directed lugs 98, see Figs. 7 and 10, which are received within complementary grooves 99 formed in the adjacent flanges of the channel members 87 and 88. The lugs 97 and 98 act to support the inner frame with the inner faces of its channel members 93, 94, 95 and 96 flush with the inner faces of the channel members 87, 88, 89 and 90 and spaced from the inner face of the plate 91.

The inner face of the back cover 52 is closed

6

by means of a cover plate 100 formed of the same material as the plate 91. The cover plate 100 extends from the channel member 89 nearly completely to the channel member 90 and is formed along its edge adjacent the channel member 90 with spaced hinge lugs 101. An L-shaped member has one short arm 102 extended along the outer face of the intermediate arm of the channel member 90 and a long arm 103 extended along the inner face of the back cover 52 toward the adjacent edge of the cover plate 100. The edge of the long arm 103 is formed with spaced hinge lugs 104 which fit between the hinge lugs 101 of the cover plate 100. The hinge lugs 101 and 104 are formed with aligned holes through which a hinge pin 105 extends so as to pivotally connect the cover plate 100 to the long arm 103 of the L-shaped member.

The free edge of the short arm 102 of the L-shaped member is formed with spaced hinge lugs 106 which fit between complementary hinge lugs 107 formed on the channel member 90. The hinge lugs 106 and 107 are formed with aligned holes through which a pivot pin 108 extends. Thus, the inner face of the back cover 52 can be partially opened by pivoting the cover plate 100 about the hinge pin 105 or that inner face can be completely opened by pivoting the cover plate 100 with the L-shaped member about the hinge pin 107, which latter open position of the back cover is illustrated in Fig. 7.

The inner face of the long arm 103 of the L-shaped member is formed with a recess 109, see Figs. 7, 12 and 13, having extensions 109^a aligned with openings 110 formed in the junction of the long arm 103 with the short arm 102, see Fig. 13. The openings 110 together with the recess extensions 109^a and the recess 109 provide clearance for the straps 53 to enter the hollow 40 of the back cover 52, as clearly shown in Fig. 13. As shown in Fig. 12, the short arm 102 of the L-shaped member is formed with a cutout 111 and the intermediate arms of the channel members 90 and 96 are formed respectively with holes 112 and 113 through which the binding belt 55 enters the hollow of the back cover 52.

Means is provided for retaining the cover plate 100 in a closed position with respect to the inner face of the back cover 52. This means comprises a pin 114, see particularly Fig. 9, which is mounted through the free edge of the cover plate 100. The adjacent flange of the channel member 89 is formed with a hole 115 through which the free end of the pin 114 passes in the closed position 55 of the cover 100. Closely adjacent the inner face of the cover plate 100, the pin 114 is formed with an enlargement 116 which when forced through the hole 115 engages the inner face of that adjacent flange of the channel member 89 60 retaining the cover plate 100 in its closed position.

Mounted horizontally in position between the channel members 95 and 96 of the inner frame, there are horizontal vertically spaced rack bars 117 formed of L-shaped stock. The ends of the rack bars 117 are welded to the inner edges of the channel members 95 and 96 with arms directed toward one another and arms extended toward the cover plate 100. The arms of the rack bars 117 which are directed toward the cover plate 100 are formed with rounded teeth 118, best shown in Figs. 9 and 11. The straps 53, within the hollow of the back cover 52, pass along the outer edges of the rack bars 117 and 70 the binding belt 55 passes between the rack bars

75 the binding belt 55 passes between the rack bars

midway thereof. As shown in Fig. 8, the top and bottom edges of the back sheet 54, after entering the hollow of the back cover 52 through the opening 92, are slidably disposed between the adjacent flanges of the channel members 87 and 93 at the top of the cover and the channel members 88 and 94 at the bottom of the cover.

Within the hollow of the back cover 52, the straps 53, the back sheet 54 and the binding belt 55 are joined together at their ends as an integral unit. The joining of those parts is accomplished by a strip of metal 119, see Figs. 8 and 9, which is extended continuously along the bottom face of the back sheet 54 adjacent the end thereof. Extended along the other face of the back sheet 54, between the rack bars 117 and the channel members 93 and 94 of the inner frame, there are metal strips 120, see Figs. 7 and 8. The outer ends of the strips 120 have their end portions 120a, see Fig. 8, bent to ride along the inner face of the flanges of the channel members 93 and 94 engaged by the back sheet 54. Screws 121 are passed through the strips 120, the back sheet 54 and threaded into the strip 119.

Superimposed on the ends of the strips 120, adjacent the outer sides of the rack bars 117 are the ends of the straps 53. Short metal plates 122 are superimposed on the ends of the straps 53 and screws 123 are passed through the plates 122, the ends of the straps 53, the strips 120, the back sheet 54 and threaded into the strip 119 to securely mount the ends of the straps 53 in position.

Between the rack bars 117, the exposed face of the end portion of the back sheet 54 has positioned thereon superimposed metal strips 124 and 125. The metal strip 124 is formed of material having the same thickness as the material of the rack bars 117 and is used as a spacer for raising the inner face of the metal strip 125 to the level of the exposed face of the inwardly directed arms of the rack bars 117. The metal strip 124 has its ends stopped short of the inwardly directed arms of the rack bars 117 and the metal strip 125 has its ends riding on the exposed faces of the inwardly directed arms of the rack bars, see particularly Fig. 8. Screws 126 are passed through the metal plates 124 and 125, through the back sheet 54 and are threaded into the metal strip 119 joining those parts together as an integral unit. Thus, the ends of the straps 53 and the back sheet 54 are joined together for unitary movement relative to the rack bars 117.

Latch means is carried by the metal strip 125, for securing the ends of the straps 53 and the back sheet 54 in desired adjusted positions with relation to the rack bars 117. The latch means is characterized by a latch plate 127 which extends along the edge of the strip 125 facing the channel member 96. The edge of the metal strip 125 is formed with spaced curled portions 128 which are received between complementary spaced curled portions 129 formed on the adjacent edge of the latch plate 127. Extended through the curled portions 128 and 129 there is a long pivot pin 130 pivotally mounting the latch plate 127 on the metal strip 125. The free edge of the latch plate 127 is formed with spaced tubular portions 131. Fixedly extended through the tubular portions 131, there is a latch bar 132, circular in cross-section, which has its ends projected beyond the outermost tubular portions 131. The projected ends of the latch bar 132 engage between the teeth 118 of the rack bars 117 and retain the straps 53 and the back sheet 54 in

adjusted positions with relation to the rack bars 117.

Resilient means is provided in connection with the pivot pin 130 for urging the latch plate 127 into a pivoted position in which the ends of the latch bar 132 are retained in position between the teeth 118. That resilient means comprises a coil spring 133 which is wound on the pivot pin 130 and which has its ends bearing on the exposed faces of the metal strip 125 and the latch plate 127 urging the latch plate 127 into a position in which the ends of the latch bar 132 are engaged with the teeth 118. It being appreciated, of course, that the teeth 118 of the rack bars 117 must be aligned for the ends of the latch bar 132 to be engaged between adjacent teeth.

Means carried by the latch plate 127 and controlled by the binding belt 55 is provided for pivoting the latch plate 127 against the action of the coil spring 133 to disengage the ends of the latch bar 132 from the teeth 118 freeing the ends of the straps 53 and the back sheet 54 to be adjusted with relation to the rack bars 117 and the back cover 52. That means is characterized by a finger 134 which is fixedly mounted at one end to the inner or bottom face of the latch plate 127 and which has its free end exposed over the coil spring 133. The free end of the finger 134 carries a headed stud 135 which is passed through a complementary hole 136, see Fig. 9, formed in the binding belt 55. The headed stud 135 functions to releasably connect the finger 134 and the binding belt 55. The finger 134 is formed of flexible material but the material used must have sufficient rigidity to overcome the action of the coil spring 133 when pressures are applied to the free end of the finger 134. From Fig. 9, where only a portion of the cover plate 100 is shown at the right-hand side of the figure, it will be noted that the finger 134 is given a natural bias to have its free end project from the open side, of the back cover 52 when the cover plate 100 is in its open position. When that cover plate 100 is closed it presses inward on the free end of the finger 134 pressing it into the hollow of the back cover 52.

From the finger 134, the free end of the binding belt 55 is again passed to the exterior of the back cover 52 through aligned holes 137 and 138 formed respectively in the intermediate arms of the channel members 89 and 95. The binding belt 55 where it passes through the holes 137 and 138 of the channel members 89 and 95, respectively, functions to retain the inner frame in position within the back cover 52. The relationship of the binding belt 55 to the finger 134 is such that when the extended end of the belt 55 is pulled a pressure will be exerted on the free end of the finger 134 to pivot the latch plate 127 against the action of the coil spring 133 and disengage the ends of the latch bar 132 from the teeth 118 of the rack bars 117. Further pulling on the end of the binding belt 55 will draw the straps 53 and the back sheet 54 further into the back cover 52 reducing the operative lengths of the straps and the back sheet between the back edges of the covers 51 and 52. When the pull on the binding belt 55 is relaxed, the coil spring 133 will function to pivot the latch plate 127 back to its starting position re-engaging the ends of the latch bar 132 with the teeth 118 of the rack bars 117 to retain the ends of the straps 53 and the back sheet 54 in their newly adjusted positions.

A U-shaped latch frame 139 has the free ends of its side arms pivotally attached to hinge plates 140 in turn secured to the exposed flanges of the

channel member 96. The latch frame 139 is of a length to extend completely across the open side of the back cover 52 to the channel member 95 of the inner frame. In the operative position of the latch frame 139, illustrated by the full lines in Fig. 7, that frame extends across the latch plate 127 and is engaged by the inner face of the cover plate 100, when in its closed position as partially shown at the right-hand side of Fig. 9, to retain that latch plate in a pivoted position in which the free ends of the latch bar 132 will be retained engaged with the teeth 118 of the rack bars 117. Thus, the U-shaped latch frame 139 functions as an auxiliary to the coil spring 133 to retain the latch plate 127 in an operative position in the closed position of the cover plate 100. The inoperative pivoted position of the latch frame 139 is indicated by the dot and dash lines 139' in Fig. 7.

The free end of the binding belt 55 is formed with a line of spaced perforations 141 and the pin 142 carried by the cover plate 100, is formed with a pin-like extension 144, see particularly Fig. 9, which in the closed position of the cover plate 100, is extended through one of the perforations 141 to secure the binding belt in the desired adjusted position of the latch plate 127. In the closed position of the book 50, the free projected end of the binding belt 55 is engaged about the free edges of the covers 51 and 52 and a headed pin 142 mounted on the outer side of the front cover 51 is passed through one of the perforations 141. From there the free end of the binding belt 55 is slipped through a loop 143 mounted on the outer face of the cover 51 rearward of the headed pin 142. Thus, the binding belt 55 is also used for securing the book 50 in a closed position and, if desired, any known type of lock can be provided in connection with the projected free end of the binding belt 55 for locking the book in its closed position.

When the spacing between the covers 51 and 52 is small, as when there are few inserts between the adjacent faces of those covers, the free end of the belt 55 may be too long and unwieldy if that belt is made of one continuous length, long enough to engage about the book when the covers are expanded to their maximum as controlled by the operative lengths of the back sheet 54 and the straps 53. To overcome that difficulty the binding belt can be made, if desired, of several end aligned sections with the ends of those sections joined together by suitable splicing or lacing so that some of the sections can be removed to reduce the operative length of the binding belt when the spacing of the covers is small.

It is believed that from the foregoing description the method of adjusting the position of the exposed lengths of the straps 53 and the back sheet 54 between the back edges of the covers 51 and 52 will be evident. However, it is pointed out that the toothed pieces of metal 81 and the inwardly directed arm 81 of the L-shaped strip of metal 60, of the front cover 51, provide a coarse adjustment whereby the reserve lengths of the straps 53 and the back sheet 54 can be extended or absorbed, as desired. On the other hand, the latch plate 127 and related mechanism of the back cover 52 provides a means whereby the operative lengths of the straps 53 and the back sheet 54 can be adjusted within very small degrees to obtain the desired positioning of the covers 51 and 52 with relation to each other.

In Fig. 2 there is illustrated details of the post hanger which is used for mounting the articles to be filed in position on the straps 53 and between

the adjacent faces of the covers 51 and 52. Each of the post hangers is formed of a relatively thin strip of metal 144 which is somewhat flexible although it need not be flexible. Extended inward from the back edge of the strip of metal 144 there is a spaced cutout 145 which continues at its top edge into an upwardly extended recess 146. The recess 146 is located midway of the side of the metal strip 144 dividing off a downwardly projected finger 147. The cutout 145 is sufficiently wide to permit the strap 53 to be passed therethrough to be aligned with the recess 146 after which the metal strip 144 can be moved downward to dispose the strap 53 within the recess 146 and in front of the finger 147, as shown in full lines in Fig. 2. The strap 53 can, if desired, be made smooth and be reinforced by the application of resinous material to the top and bottom edges thereof so that the post hangers will have free movement along the lengths of those straps.

Similarly, the front edge of the metal strip 144 has a cutout 155 which continues at its bottom into a downwardly extended recess 156. The recess 156 is located midway of the width of the metal strip 144 dividing off a finger 157 which is extended upward to receive a clip, to be hereinafter described carried by the respective article to be filed. The cutout 155 and recess 156 are arranged out of horizontal alignment with relation to the cutouts 145 and recess 146 so that the metal strip 144 can be made of a narrow strip of metal.

Means is provided for obstructing the free end 35 of the finger 157 so as to retain the clip in position on the finger. The obstructing means includes an elongated lock strip 161 which engages the free end of the respective finger 157 to retain the clip from sliding therefrom.

40 Pivots on the upper end portion of the strip of metal 144 adjacent the free end of the lock strip 161 there is an operating cam 163. The cam 163 is pivotally retained in position on the upper end portion of the strip of metal 144 by means of a pivot pin 164. The top of the cam 163 is formed with an upwardly extended finger 165 which projects above the top end of the metal strip 144 providing a finger grip by which the cam can be pivoted. When the cam 163 is pivoted, it in turn pivots the lock strip 161 disengaging it from the free end of the respective finger 157. When the operating cam 163 is pivoted through ninety degrees its flat bottom end will function to hold the lock strip 161 in its inoperative position in which the free end of the finger 157 will be unobstructed.

In Fig. 2 the filed item 166 is in the form of a thin pamphlet and is provided along its back edge with spaced clips 167 which are properly spaced to be received over the fingers 157. Each of the clips 167 is formed of a piece of relatively stiff wire has one end portion bent into a coil 168 to be slipped over the free end portion of the respective finger 157. The other end portion of the piece of wire has a point 169 and is bent to be extended into and then out of the back of the pamphlet, as shown in Fig. 2. With the coil 168 engaged upon the finger 157, as shown in Fig. 2, and the lock strip 161 in its operative position 60 obstructing the free end of the upper finger 157 it will be appreciated that the pamphlet will be retained in position on the post hanger. If the post hanger is then engaged with the strap 53, the pamphlet will then be removably filed between the adjacent faces of the covers 51 and 52.

of the book. The use of the clip 167 provides a ready means by which the filed item 166 can be removed from the post hanger for use outside of the book, without removing the post hanger from the strap 53 so that the post hanger marks the place where the item is to be returned to the book. At the same time, the complete assembly including the post hanger can be separated from the straps 53 when the filed item is to be removed from the file to be discarded or for other reasons.

Provided to be removably mounted on the straps 53 between different groups of articles filed in the book 50, there are partition sheets 170 illustrated in detail in Fig. 2. The partition sheets 170 are provided to separate the different groups of items filed in the book 50 and each is comprised of a main body portion 171 formed of heavy cardboard, synthetic resin material or metal and can be inscribed on the face thereof or have secured to the face thereof a label carrying an inscription as to the nature of the items which follow that particular partition sheet in the book 50. Whether the face of the main body portion 171 is inscribed directly or has a label secured thereto will depend on the nature of the material used to form the main body portion.

A strip of metal 172 is formed along its one vertical edge with a groove 173, into which the adjacent edge of the main body portion 171 is received. Spaced rivets 174 are engaged through the main body portion 171 and the strip of metal 172 joining those parts together. The other vertical edge of the metal strip 172 is formed with spaced hinge lugs 175 between which there is received spaced hinge lugs 176 formed on a second metal strip 177. The hinge lugs 175 and 176 are formed with aligned holes for the passage of a pivot pin 178 to pivotally interconnect the metal strips 172 and 177. If the main body portion 151 is formed of metal or synthetic resin, there is no need for using the metal strip 172, as the back edge of the main body portion can be hinged directly to the metal strip 177.

The back edge of the metal strip 177 is formed with cutouts 179 which are properly spaced to receive the straps 53, as shown in Fig. 2. Closely adjacent the back edge, the metal strip 177 is formed with a tubular passage 180 which traverses the cutouts 179 closely adjacent their mouths or open sides. A long pin 181 is slidably and axially removably received within the passage 180 for engaging behind the straps 53, see Fig. 2, with those straps in position in the cutouts 179 for mounting the partition sheets 170 removably in position on those straps. When the pin 181 is axially slid from the tubular passage 180, the partition sheet 170 is free to be removed from the straps 53, through the open sides of the cutouts 179.

Also, positioned on the straps 53, between the inner faces of the covers 51 and 52 of the book and the articles filed therein, there are strap tensioning panels 182. Details of the construction and the position of those panels on the straps 53 is illustrated in Figs. 2, 12 and 13. In the latter figures, the filed items have been omitted for the sake of clarity, but it is appreciated that those items will be in the space between the adjacent faces of the panels having particular regard for Figs. 12 and 13. The tensioning panels 182 are formed of metal or synthetic resin material and are provided substantially midway of their sides with cutouts 183 through the inner ends of which the straps 53 pass, as shown in Figs. 2 and 13. Between the cutouts 183 and

at a point aligned with the binding belt 55, the back edge of the panels 182 are formed with cutouts 185 through which the belt 55 passes, as shown in Figs. 2 and 12.

Means is provided for releasably retaining the tensioning panels 182 in position on the straps 53. The releasably retaining means is characterized by end aligned tube sections 300 which are positioned against the one face of the each of the panels 182 on opposite sides of the cutouts 183. The tube sections 300 are retained in position by means of straps 301 mounted in position over the tube sections 300 and secured in position on the panels by means of rivets 302. Slidably extended through the tube sections 300 there is a long pin 303 which is passed behind the straps 53 mounting the panels 182 in position thereon. At one end, the pin 303 is provided with an enlarged head 304 by which a grip can be had on the pin for pulling the same out of the tube sections 300 to free the panels 182 from the straps 53 for removal when desired. By this construction, the panels 182 can be easily removed from the straps 53, and, if desired, additional panels 25 can be inserted between the adjacent faces of the filed articles at any position along the lengths of the straps 53 in the completely expanded position of the book.

When the book 50 is closed with filed items in position on the straps 53, the back edges of the tensioning panels 182 engage the inner faces of the back sheet 54, as shown in Figs. 12 and 13 and push forward on the straps 53 properly tensioning those straps between the back edges of 35 the front cover 51 and the back cover 52. Those panels 182 serve to rigidly retain the straps in position and so retain the filed items from shifting their positions relative to one another and to the covers while the book is being carried about 40 in its closed position.

Extended vertically along the outer face of the back sheet 54 between the rear edges of the covers 51 and 52, there is a vertically extended tablet member 186. The tablet member 186 is formed 45 of resinous plastic material or other material upon which notations regarding the contents of the book 50 can be inscribed. Secured to the top and bottom edges of the tablet member 186, by means of rivets 187, there are spaced metal 50 clips 188. The clips 188 are of U-shaped configuration with their open sides directed toward one another so that they can be slipped over the top and bottom edges of the back sheet 54.

The clips 188 permit the tablet member 186 55 to be slid along the operative length of the back sheet 54 so that the tablet member can always be positioned midway between the back edges of the covers 51 and 52 regardless of the spacing of those covers. With the face of the tablet 60 member 186 inscribed with a notation regarding the contents of the book, the proper book can be quickly identified when a number of books are positioned side by side on a shelf.

It is believed that the manner of using the 65 filing book of the present invention will be self-evident from the foregoing description without a detailed explanation of the operation. From the explanation, it is apparent that there has been provided a convenient book-type filing device in 70 which the operative content space is only limited by the lengths of the straps 53, the back sheet 54 and the binding belt 55 and which content space can be quickly increased and decreased in size as the contents may require, without the use of any tools. Furthermore, the binder pro-

13

vides a novel means for filing any type of fluctuating records as each item is easy to insert and is held securely in place and each can be easily removed without disturbing any of the other filed items.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A loose leaf filing book comprising hollow front and back covers, spaced straps and a binding belt extending between the back edges of said covers, hinged cover plates for the hollow front and back covers, means for adjusting the straps and binding belt comprising teeth engaging the straps and binding belt on one hinged cover plate, an inner frame co-extensive with and mounted in the other hollow cover, said inner frame having channeled edges, a bar extending across said inner frame to which is attached one end of the straps, the ends of said bar being slidably mounted in the channels of said inner frame, parallel rack bars extending from the inner edge to the outer edge of the inner frame, a latch mechanism pivotally mounted on said bar comprising a projecting finger, a latch plate and a latch bar for engaging the rack bars, said finger having a projection thereon, said belt engaging said projection and extending beyond the hollow cover, and a latch frame pivotally mounted to the inner edge of the inner frame overlying the latching mechanism and locking the same to engage the rack bars when the cover plate is fastened down on the hollow cover.

2. A loose leaf filing book comprising hollow front and back covers, said hollow covers having channeled frames, spaced straps and a binding belt extending between the back edges of said covers, hinged cover plates for the hollow front and back covers, means for adjusting the straps and binding belt comprising teeth engaging the straps and binding belt on one hinged cover plate, an inner frame co-extensive with and mounted

14

in the other hollow cover, means for retaining the inner frame within the hollow cover comprising lugs on the inner edge of the frame projecting into the channels of the cover and projections on the outer edge overlying the channel frame of the cover, said hollow cover and frame having matched openings through which the binding belt passes, said inner frame having channeled edges, a bar extending across said inner frame to which is attached one end of the straps, the ends of said bar being slidably mounted in the channels of said inner frame, parallel rack bars extending from the inner edge to the outer edge of the inner frame, a latch mechanism pivotally mounted on said bar comprising a projecting finger, a latch plate and a latch bar for engaging the rack bars, said finger having a projection thereon, said belt engaging said projection and extending beyond the hollow cover, and a latch frame pivotally mounted to the inner edge of the inner frame overlying the latching mechanism and locking the same to engage the rack bars when the cover plate is fastened down on the hollow cover.
